CLAIM

The ornamental design for a model vehicle electronic speed control case as shown and described.

DESCRIPTION

FIG. 1 is an upper, left, front perspective view of a model vehicle electronic speed control case showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is an upper plan view thereof;

FIG. 7 is a lower plan view thereof;

FIG. 8 is an upper, right, rear perspective view thereof; and, FIG. 9 is a lower, right, rear perspective view of the model vehicle electronic speed control case.

In the drawings, the broken lines illustrate portions of the model vehicle electronic speed control case that form no part of the claimed design.
